J. B. DOBSCHUTZ

HAIRPIN

Filed May 15, 1922

FIG. 1

FIG. 3

FIG. 2

INVENTOR
JENH B. DOBSCHUTZ
By Edward E. Longan
ATTY

UNITED STATES PATENT OFFICE.

JEHU B. DOBSCHUTZ, OF ST. LOUIS, MISSOURI, ASSIGNOR OF ONE-HALF TO WILLIAM P. HILL, OF ST. LOUIS, MISSOURI.

HAIRPIN.

Application filed May 15, 1922. Serial No. 560,875.

To all whom it may concern:

Be it known that I, JEHU B. DOBSCHUTZ, a citizen of the United States, and resident of the city of St. Louis and State of Missouri, have invented certain new and useful improvements in Hairpins, of which the following is a specification containing a full, clear, and exact description, reference being had to the accompanying drawings, forming 10 a part hereof.

My invention relates to improvements in hairpins, and has for its primary object the construction of a pin which when applied to the hair in use, will interlock itself 15 with the hair and prevent its accidental falling out.

In the drawings,

Fig. 1 is a plan view of my hairpin.

Fig. 2 is a fragmental view, illustrating 20 the position in which the strands of the hair assume when the device is in use.

Fig. 3 is a plan view of a slightly modified form.

Referring to the drawings:

25 4 indicates the prongs which may be corrugated as at 5, or if desired the same may be left straight. Formed integral with the prongs is the head of the hairpin 6, the upper portion 7 of which represents the segment of a circle. The lower portion of the head 7 is provided with downwardly curved 30 portions 8, and upwardly projecting portions 9.

When my device is applied to the hair, 35 the hair will enter between the prongs 4 and become seated in the downwardly curved portions 8 on the outside of the upwardly projecting shoulders 9. In other words, the hair will become lodged behind the upwardly 40 projecting shoulders 9 and the hairpin will be held in place by the hair and will not become accidentally dislodged.

In Fig. 3 I have shown a slightly modified form, wherein the upper portion 7 of 45 the head is slightly flattened, as at 10. The exact curvature of the upper portion of the head is not material, the essential feature being the downwardly bent portions 8, and the upwardly projecting shoulders 9, for 50 engaging the hair.

It will be observed that the downwardly

bent portions and the upper projecting shoulders which extend into the head form on each side of the prongs, troughs or pockets in which the hair which has passed between the prongs is received and lodged. 55 See Fig. 2 for illustration.

Having fully described my invention, what I claim is:

1. A hairpin comprising a pair of spaced 60 apart prongs, a head having a downwardly curved upper portion formed integral with the prongs, said head being provided in its lower portion with downwardly curved bent portions spaced apart from and on the outside of the prongs, and adjacent the prongs with upwardly extending portions forming shoulders, said shoulders and downwardly bent portions being spaced apart and forming pockets adapted to engage the hair when 70 the pin is in use to receive and prevent it from falling out.

2. A hairpin comprising a pair of spaced apart prongs, a head formed integral with the prongs and communicating with the 75 space between the prongs, said head having its upper portion curved and said head being provided in its lower portion with downwardly curved bent portions spaced apart from the outside of the prongs, and adjacent 80 the prongs with shoulders extending upwardly within the head and above the downwardly curved portions, said shoulders and downwardly bent portions spaced apart 85 and forming pockets adapted to receive and engage the hair which has passed between the prongs when the pin is in use to prevent it from falling out.

3. A hairpin comprising a pair of prongs, a curved head formed integral with said 90 prongs, said head being provided in its lower portion with downwardly curved bent portions and adjacent the prongs with upwardly bent portions spaced apart from the downwardly bent portions, said upwardly 95 bent portions being integral with the prongs and forming shoulders and pockets adapted to engage the hair for securing the pin therein when in use.

In testimony whereof, I have signed my 100 name to this specification.

JEHU B. DOBSCHUTZ.
